United States Patent Office

Des. 184,190
Patented Dec. 30, 1958

184,190

DISPLAY STAND FOR CANDY OR THE LIKE

David A. McCowan, Toronto, Ontario, Canada

Application October 4, 1957, Serial No. 47,962

Claims priority, application Canada August 31, 1957

Term of patent 14 years

(Cl. D80—9)

FIG. 1

Des. 184,190

PAGE 2

I claim:

The ornamental design for a display stand for candy or the like, as shown.
